UNITED STATES PATENT OFFICE.

ALFRED GODFREY, OF LONDON, ENGLAND.

PACKAGING-MACHINE.

1,283,153.

Specification of Letters Patent. Patented Oct. 29, 1918.

Application filed May 3, 1913. Serial No. 765,382.

To all whom it may concern:

Be it known that I, ALFRED GODFREY, of the city of London, in the county of London, England, engineer, have invented a certain new and useful Packaging-Machine, of which the following is a specification.

This invention relates to the manufacture of cases in paper, cardboard or other similar material and the packing of cigarettes and like goods therein. According to the invention the paper or cardboard blank can be fed into the machine to a registered position, is held firmly and cut to the desired shape, the proper number of cigarettes or other articles are fed automatically from a hopper on to the cut and creased blank, the dust from the cigarettes is conveyed away from the working parts, the consolidation of the cigarettes as a compact series is effected, the blank is folded at various parts with sharp corners at the various edges into the form of a case, certain parts receive a coating of gum or other agglutinant at the necessary edges from adjustable mechanism arranged to deliver strained gum or other agglutinant to the surfaces, the parts folded down are pressed down into contact so that they adhere and are mechanically fed into a contractile drying chamber for final drying to make a secure passage and finally the case containing the cigarettes is automatically discharged from the machine in a complete condition ready for sale.

In order that my invention may be better understood, I will now proceed to describe the same in relation to the accompanying drawings, reference being had to the letters and figures marked thereon. Like letters refer to like parts in the various figures.

Figure 1 is a side elevation of a machine constructed in accordance with my invention.

Fig. 1^a is an elevational view of the spring bumper in detail.

Fig. 1^b is a plan view of Fig. 1 with some portions removed to show the parts beneath.

Fig. 2 is a view of a blank of cardboard or paper as fed into the machine and

Fig. 3 is a view of the same blank as cut and creased before folding.

Fig. 4 is a detail view of the cut blank feeding mechanism,

Fig. 4^a is a plan of the grippers and oper-

ating gear of the cut blank feeding mechanism,

55

Fig. 5 is a view of the cigarette feeding mechanism.

Fig. 5^a is a side elevation of the hopper and agitating gear,

Fig. 5^b is a plan of one hopper showing the feeding fingers and receiving platform.

Fig. 5^c shows a blank with the cigarettes fed on in place,

Fig. 5^d shows in two views the dust chutes for conveying the dust tobacco discharged from the cigarettes owing to the reciproca- 65 tion of the feeding tray.

Fig. 5^e is two views of the side pieces on the plunger for locating the cigarettes in their proper position in the case during the 70 descent of the plunger.

Fig. 6 is a view of the folding mechanism for the first two folding operations.

Fig. 6^a is a view of the partially formed case with contained cigarettes after the first 75 folding operation.

Fig. 6^b is a view of the case after the second folding operation.

Fig. 6^c is a detail of mechanism of modified construction for effecting the second 80 folding operation and for pushing the packet.

Fig. 6^d is a view of adjustable means for taking up wear from the cam surface.

Fig. 7 is a view of the mechanism for pro- 85 ducing a sharp corner at the ends of the case.

Fig. 8 is a view of the mechanism for the third folding operation.

Fig. 8^a shows the case so folded.

Fig. 9 is a view of the mechanism for the 90 fourth folding operation.

Fig. 9^a shows the case as folded.

Fig. 10 is a view of the folding mechanism for doubling the packet up when completed.

Fig. 10^a shows the case in its final form 95 ready for sale.

Fig. 10^b is a detail view of a modified form of mechanism for the doubling up of the packet.

Fig. 10^c is a side elevation of the drying 100 chamber showing the means for providing the collapsible sides.

Fig. 10^d is a sectional end elevation of the same.

Fig. 10^e shows a plan and sectional side 105 elevation respectively of an eccentric adjust-

ment for varying the axial position of the rollers which co-act with any of the cams for taking up wear.

Fig. 10^f shows the spring means for preventing the packets from irregular displacement in the drying chamber.

Fig. 10^e shows a portion of the drying chamber carrying a retaining nose.

Fig. 11 is a detail sectional part elevation 10 of the machine showing the gumming mechanism.

Fig. 11^a is a detail view of the operating gear of the gumming mechanism.

Fig. 11^b is a detail view of adjusting means 15 for the gumming roller and box in relation to the plunger and spout.

Fig. 11^c is a side elevation of the apron provided with dust channels and openings opposite the gumming pads.

20 Fig. 11^d is a plan of the same.

Fig. 11^e is a gumming device regulating rod.

Fig. 12 shows a modified construction for making a single case.

25 Fig. 12^a is a view of the cut and creased blank before insertion into the machine.

Fig. 12^b shows the first folding operation.

Fig. 12^c shows the second folding operation.

30 Fig. 12^d shows the third folding operation.

Fig. 12^e shows the fourth folding operation.

Fig. 12^f shows the fifth folding operation.

35 Fig. 12^g shows the case completed. Fig. 12^h shows two views in elevation of the details of the mechanism for folding down the flap *p*⁴. Fig. 12ⁱ shows two views in elevation of the details of the mechanism by 40 means of which the final closure of the case is effected.

To carry my invention into effect I arrange a feed table *a* on which the sheets of paper or cardboard can be fed by hand and 45 in connection with such table I arrange advancing and retiring fingers *b* which have a reciprocating motion given to them by a cam *b*¹ operating the bell crank *b*² connected by means of a forked end *b*³ with a pin *b*⁴ carried by a slide *b*⁵ to which the fingers *b* are rigidly attached; the motion of the bell crank *b*² in the opposite direction to that given it by the cam *b*¹ is effected by a spring *b*⁶.

55 The ends of the fingers *b* are adapted to engage with the edge of the paper or cardboard lying on the table *a* and feed it forward to a position of definite register and to retire again to engage the next piece of 60 paper as the machine moves.

The paper blank, which may have been cut and creased in any suitable manner (not shown), is seized by gripping means consisting of a slide *d* adapted to reciprocate on the 65 bed of the machine and having at one end

pivoted grippers *d*¹, the end *d*² of which holds the paper tightly upon the upper surface of the slide *d*. The slide *d* is reciprocated along the bed by means of a pivoted forked arm *d*³ adapted to engage with a pin *d*⁴ carried by a slide *d* and having a roller *d*⁵ rotatably carried on the lever *d*³ and engaging with a cam *d*⁶.

The grippers *d*¹ are pressed into their operative position by means of a spring pressed 75 plunger *d*⁸ engaging on the underside of the rear arm of the grippers.

In order to open the grippers the rear arm has a lateral extension *d*⁹ which contacts during the reciprocating movement with a 80 spring pressed pivoted switching arm *d*¹⁰ so that on the forward movement the projection *d*⁹ engages on the under inclined face of the arm *d*¹⁰, until nearing the end of the reciprocating stroke the extension *d*⁹ trips 85 past the lower end of the inclined surface so as to allow the spring pressed plunger *d*⁸ to force the grippers into contact with the paper. On the return stroke, the extension *d*⁹ rides over the upper inclined surface of 90 the arm *d*¹⁰ which being spring pressed is forced in a downward direction against such spring and thus allows the extension *d*⁹ to pass freely over it and when the said extension has passed the arm *d*¹⁰ the latter rises 9 again under the action of its spring into position ready for the next forward stroke. The arm *d*¹⁰ is prevented from an upward movement above the position shown in Fig. 4 by a fixed stop *d*⁷ against which it abuts. 1

As the grippers *d*¹ reach the right hand end of their stroke so that the cut blank is disposed over the folding die *e* the lateral extension *d*⁹ is disposed under a pivoted arm *d*¹¹ operated by a connecting rod *d*¹², pivoted 1 lever *d*¹³ and cam *d*¹⁴ so as to raise the end *d*² of the grippers *d*¹ from the paper and release it. In order to take up the momentum of the slide *d* at the end of the backward stroke a spring buffer *d*¹⁵ is arranged in the 1 frame shown on an enlarged scale in Fig. 1^a.

On each side of the machine is arranged a cigarette hopper *f* having at its discharge end a reciprocating tray *f*¹ divided into spaces by parallel ribs *f*² so as to allow a 1 proper number of cigarettes in regular order and in not less than two superposed layers, as shown in Fig. 5^a, to be received from the hopper. The side wall of the hopper farthest from the fingers *f*¹ is cut away sufficiently to allow only one row of cigarettes to be pushed out of the hopper by the fingers. This tray *f*¹ is reciprocated to and fro during a certain period of operation of the machine by means of a pivoted lever *f*³ and cam *f*⁴ one segment of the cam being provided with an undulating surface *f*⁵ for shaking the cigarettes down and preventing any jamming thereof, and another segmental portion *f*⁶ of circular periphery to maintain the 1

paper in the tray *f*¹ during the time of its reciprocation.

tray f' stationary during the feeding of the cigarettes from the tray on to the paper blank.

In order to avoid any inconvenience from the presence of tobacco dust shaken out from the cigarettes, in the process of being fed down on to the tray f' , inclined chutes f^{14} are provided at each side of the bed f^{15} (Fig. 5^a) on which the tray f' reciprocates and another inclined chute f^{16} common to the two chutes f^{14} leads the dust away to a safe point of discharge.

This feeding operation is effected by means of a series of fingers f^7 correspondingly disposed to the spaces in the tray, the said fingers being moved to and fro by means of forked rocking levers f^8 , connecting rod f^9 and a cam f^{10} , the return stroke being effected by a spring f^{11} shutting against a fixed stop f^{12} carried on the frame of the machine. The levers f^8 and connecting rod f^9 are shown in full and dotted position in Fig. 5 indicating the extent of the motion.

The cigarettes when fed on to the cut blank have to pass between two edges f^{13} forming a funnel shaped passage by which the cigarettes are closed up one against the other into a width which is less than that occupied by them when on the tray f' . The mechanism is shown in Fig. 5^b, and the cigarettes assume the position on the cut blank as indicated in Fig. 5^c.

The device upon which the blank rests during the preceding operation consists of a rising and falling table e' mounted on a parallel link e^2 the pivots e^3 of which are mounted on the frame of the machine, the upper pivot e^3 (Fig. 4) being journaled in a sliding block e^{16} on each side of the upper member e^2 and adapted to be supported in parallel guides e^{17} mounted on the frame of the machine. The object of its arrangement is to allow the table e' to only have a vertical motion, the effect of the radial motion of the upper member e^2 being neutralized by the sliding of the blocks e^{16} in their guides e^{17} against the pressure of a spring e^{18} behind each block e^{16} . As it is important that the level of the table e' should register to a definite position at the bottom of the stroke, adjustable stops e^{26} are arranged on the frame for the table to rest on, Figs. 4, 8 and 9. These parallel links are operated by a roller e^4 contacting with a cam e^5 . Immediately over the table e' is a reciprocating plunger e^6 mounted on the frame of the machine by means of antifriction rollers e^7 . This plunger is adapted to be lifted by a pivoted arm e^8 , lever e^9 , connecting rod e^{10} , pivoted lever e^{11} and roller e^{12} , which latter contacts with the cam e^{18} . The plunger e^6 has at its lower end a spring pressed projection e^{14} having an effective depth after compressing the spring substantially the same as the depth of the cigarettes, and in addi-

tion there is arranged on each side of the plunger e^6 pieces e^{19} (Fig. 5^e) which have a depending curved portion e^{20} so arranged that the end cigarettes of each layer are restrained from rolling outward on the descent of the plunger e^6 .

It must be understood that the lower surface of the projection e^{14} first contacts with center portion e^{15} in the proper blank so as to grip it between the projection e^{14} and the table e' and at the same time to form an abutment on each side against which the cigarettes are pressed by the feeding fingers f^7 , the end surface of the plunger e^6 now presses upon the two layers of cigarettes and drives the blank with the cigarettes in place into the folding die e , the table e' simultaneously dropping to allow this operation to be effected. In passing down through the folding die e the sides of the blank are folded as indicated in Fig. 6^a, and in this condition the whole gumming operation is effected.

Upon the upper portion of the frame of the machine a gum reservoir g is disposed the side of which toward the plunger e^6 is open and is closed up by a constantly rotating roller g' which runs in the direction of the arrow.

In order to prevent any dust collected by roller g' from getting into the reservoir g a strainer g^{28} of wire gauze is disposed across the reservoir g and a knife g^{29} is arranged at the edge of the gauze so as to contact with the periphery of the roller g' in order to scrape off the gum and dust therefrom and deliver it on to the top of the gauze for straining it. In Fig. 11^b is shown an adjusting arrangement, for the relative position of the gumming roller g' and plunger to one another comprising a screw g^{30} passing through a lug g^{31} fastened to the frame the said screw bearing against the reservoir g and a locking screw g^{32} passing through the reservoir g and screwing into the center of the screw g^{30} so as to lock the same firmly against rotation and tightly against the reservoir g .

In the lower part of the gum reservoir g is a gum throttle g^2 rotatably mounted in the ends of the reservoir and means for adjustment by hand are provided so that the space between the gum throttle g^2 and the roller g' can be adjusted as desired to give a proper thickness of gum layer upon the periphery of the roller g' . When no gum is required the throttle g^2 can be turned into the position indicated in Fig. 11 under which condition practically no gum is carried by the roller g' from the reservoir. The roller g' is driven by a pulley g^3 through gearing g^4 and is operated by a belt g^5 upon the pulley g^6 on the first motion shaft m' of the machine.

Upon the plunger e^6 a gumming frame g^7 is pivoted at g^8 having a series of gumming

pads g^9 adapted to contact with the film of gum on the periphery of the roller g' during the reciprocation of the plunger e^6 ; the surface speed of the roller g' and the pads g^9 at the moment of contact being uniform.

The frame g^7 is rocked about its pivot g^8 by means of a cranked lever g^{10} mounted on a vertical shaft g^{11} the lever g^{10} carrying at its end a depending rod g^{12} , the end of which contacts with the roller g^{13} of the frame g^7 .

The vertical shaft g^{11} is mounted in bearings g^{14} and at its lower end carries an arm g^{15} having a roller g^{16} engaging with a cam g^{17} .

The roller g^{16} is maintained in contact with the cam g^{17} by means of a spring pressed plunger g^{18} engaging with a lever g^{19} which latter is rigidly fixed to the shaft g^{11} , the position of the lever g^{19} on which the operative function of the gumming mechanism depends is regulated by means of a rod g^{20} sliding in the frame of the machine and having an inclined surface g^{21} which when the rod g^{20} is pushed into its upper position by the striking treadle g^{22} forces the lever g^{19} in the direction of the arrow (see Fig. 11^a) against the spring plunger g^{18} draws the roller g^{16} away from the cam g^{17} and withdraws the pads g^9 into a non-operative position.

As the plunger e^6 ascends, the gumming pads g^9 contact with the gumming roller g' and pick up a regulated amount of gum therefrom and on the descent when the pads g^9 have reached their lowest position the recess g^{23} in the cam g^{17} allows the pads to advance toward the flaps of the case and to apply gum thereto as indicated at g^{24} in Fig. 6^b. A bridge piece i^7 mounted on the frame forms a support for the paper against the pressure of the gumming pads g^9 . As the recess g^{23} moves farther on in the rotation of the cam the pads g^9 recede from the said flaps of the case and the further folding operations are then proceeded with.

As the slide d travels along on the forward stroke any tobacco dust which has fallen on the slide bed is pushed by the side d toward the table e' and would interfere with its working unless diverted. To effect this an apron e^{21} is arranged around the table e' having an upstanding fence e^{22} on three sides as shown in Figs. 11^c and 11^d. On the side where the gumming pads g^9 are disposed apertures e^{23} are arranged through which the pads g^9 can pass. The dust collects on the surfaces e^{24} and is pushed along by the front of the slide d until it reaches the dust chutes e^{25} which convey the dust away from the gumming mechanism.

The flaps h are folded down by means of a device h' which consists of pivoted fingers h^2 mounted on reciprocating carriages h^3 , the fingers h^2 being rocked about an axis 65 by means of a rod h^4 , levers h^5 , mounted on

a cross shaft h^6 and operated by a roller h^7 contacting with a cam h^8 . The reciprocation of the carriages h^3 is effected by a forked lever h^9 pivoted to the frame of the machine at h^{10} and operated by a lever h^{11} from a cam h^{12} , the forked levers h^9 being simultaneously operated by quadrant gear h^{13} , the operative motion of the lever h^{11} being made against spring pressure from a spring h^{14} through a lever h^{15} rigidly attached to 75 or forming part of one of the quadrants h^{13} , so that the return motion is effected by the spring h^{14} .

Now dealing with the case as shown in Fig. 6^a the fingers h^2 are first rotated so 80 as to fold the flaps h down upon the cigarettes as shown in Fig. 6^b by the action of the cam h^8 . The carriages h^3 are now moved laterally by means of the cam h^{12} so that the fingers h^2 on their outward lateral motion press upon the flaps h and produce a sharp corner against an upstanding wall h^{16} by means of a slight projection h^{17} on the fingers h^2 , the rods h^4 preventing the fingers h^2 rising until the carriage h^3 has 90 completed its outward motion, and in order to further insure the paper being folded down with a square corner supporting stems h^{18} are arranged on the wall h^{16} so that their operative faces stand vertically so as 95 to support the paper and prevent it from being dragged backward when the fingers h^2 are moved backward on the carriage h^3 .

In addition to the stems h^{18} a horizontal surface or table h^{19} is provided on the frame in a fixed position which co-acts with the tail end h^{20} so as to maintain the folder h^2 in a horizontal position pressing the flap h downward and holding it there firmly while the carriage h^3 is being retired. When the carriage h^3 is in its forward position the tail end h^{20} of the folding fingers h^2 clears the table h^{19} thus enabling the tail end h^{20} to drop and the folders h^2 to be raised. It must be understood that the plunger e^6 is 100 of less width than the double packet so as to enable the flaps h to be folded down without contact therewith. As the carriages h^3 commence their outward motion the plunger e^6 begins to rise so as to leave room for 110 the flaps i to be folded down.

The slide d carrying the grippers is provided with a pushing plunger i' situated at a lower level than the grippers d' and having a finger i^2 projecting in a forward direction. As the slide d advances, the forward end of the finger i^2 comes into contact with a folding flap i^3 pivoted at i^4 on the frame of the machine and spring pressed to normally maintain a vertical position. As the flap i^3 is turned over it folds down the flap i on the cigarettes. As the plunger i' advances the face of the end i^5 comes into contact with the side of the case and pushes it into a channel i^6 under the bridge piece i^7 125 130

disposed across the upper side thereof. As the packet passes under the bridge piece i^7 the top i^8 of the case is folded down on to the cigarettes but not sufficiently closely to cause the gummed portions g^{24} to come in contact with and adhere to the flaps i and h . To effect this purpose the channel i^6 is provided with a movable roof i^9 pivoted at i^{10} on the frame of the machine and adapted to be oscillated in a vertical direction by means of the lever i^{11} , roller i^{12} and cam i^{13} . At the end of the movable roof i^9 depending fingers i^{14} are provided, which during the downward motion of the roof i^9 to close the packet first engage the top edge of the flap i^8 in the angular corner i^{17} so as to square up the case and register the position of the end with its flap i for proper attachment to the top flap i^8 . In order to register the position of the cigarettes within the two cases so that the final folding operation can be effected without disturbing the cigarettes, a regulating rib or finger i^{15} is fixedly carried on the frame of the machine and is provided with spring tongues i^{16} normally convergent to one another so as to cause an easy entry between the two layers of cigarettes as they are fed along the partially formed packet. Just at the moment of the packet completing this stage of its passage an angular nose i^{18} mounted on the slide i^5 enters between the spring tongues i^{16} and forces them into a parallel position in order to force the cigarettes outwardly against the outer sides of the case and at the same time force the outer sides of the case against the walls of the channel i^6 so as to register their position before the final attaching step of the roof i^9 is completed. As each packet is completed to this stage, it forces along the channel i^6 the packets which were previously completed. The form of the packet as now made is represented in Fig. 9^a. As each packet arrives in turn over an orifice k , in the bed of the channel i^6 as shown in Fig. 10 and is thus being deprived of any central support it drops down from its extended form in full lines to a V shape as shown in dotted lines.

Referring to Fig. 6^c a modified arrangement is shown for dealing with the folding down of the flap i ready for the flap i^8 to be folded thereon and the provision of mechanical means for feeding the closed packets along after the folding operations have been completed. In this the pivoted folding flap i^3 is operated by an arm i^{19} the pin i^{20} of which pivotally engages a block i^{21} adapted to slide in a slot i^{22} of a lever i^{23} pivoted on the cam stay i^{19} . The other end of the lever i^{23} is coupled to a bridle rod i^{24} by means of a connecting rod i^{25} having a roller i^{26} which co-acts with a cam i^{27} . On the side of the frame of the ma-

chine is pivotally mounted at the point i^{40} a slide frame i^{28} in which slides a pusher i^{29} having upstanding fingers i^{30} . The pusher i^{29} is operated by a connecting rod i^{31} , pivoted lever i^{32} roller i^{33} and cam i^{34} , 70 the return stroke being effected by a spring i^{35} . The slide frame i^{28} has a depending arm i^{36} fixedly attached thereto, said arm having a roller i^{37} co-acting with the cam i^{38} and kept into engagement therewith by a spring i^{39} . 75 The pusher i^{29} as shown in Fig. 6^c has just completed the pushing stroke on one packet and is about to retire to get behind the following packet. To do this the cam i^{38} tilts the frame i^{28} so as to lower the fingers i^{30} 80 and allow them to retire under the succeeding packet and then rise again at the back thereof. The sequence of folding down the flap i^8 , pushing the packet along and depressing and retiring the fingers i^{30} is clearly 85 shown by the relative positions of the cams i^{27} , i^{34} and i^{38} .

On the left hand side of Fig. 10 a reciprocating plunger k' is disposed in a transverse channel k^2 and is actuated by a forked 90 pivoted lever k^3 , roller k^4 , and cam k^5 . On the forward end of the plunger k' is a pivoted flap k^6 normally resting against a rear stop k^7 in an angular position. On the right hand side of the channel k^2 is the dry- 95 ing chamber k^8 .

In order to insure that the packet is properly folded and located in the proper position in the channel i^6 , a modified arrangement is shown in Fig. 10^b in which a supplemental folding flap k^9 is pivoted on the frame and is operated by a spring pressed rod k^{10} , pivoted lever k^{11} , roller k^{12} and cam k^{13} on the shaft m^2 . This flap k^9 falls into the dotted position and bends the packet 105 down to position shown in Fig. 10^b, ready for being pressed into the drying chamber k^8 . In this case the flap k^6 has a projection k^{14} which passes through a slot k^{15} in the frame and controls it without the use of 110 the stop k^7 , (Fig. 10^b). The drying chamber k^8 is formed with the top k^{16} and one side k^{17} pivoted to the main part of the chamber k^8 as to be opened at each step for the packet to enter and to close on said 115 packet so as to facilitate the entrance of each packet and passage of it or the packets that preceded it along the drying chamber k^8 . This movement is effected by a cam k^{18} on the shaft m^2 which operates a roller k^{19} 120 pivoted lever k^{20} and plunger k^{21} which latter has a beveled end adapted to engage a roller k^{22} so as to move the side k^{17} inwardly. The top k^{16} is operated by an arm k^{23} rigidly carried by the side k^{17} said arm having 125 a beveled end k^{24} co-acting with a roller k^{25} pivoted on the top k^{16} . When the plunger k^{21} is forced up it closes the side k^{17} which in turn forces the top k^{16} down. Both the side k^{16} and side k^{17} are spring pressed 130

Referring to Fig. 6^c a modified arrangement is shown for dealing with the folding down of the flap i ready for the flap i^8 to be folded thereon and the provision of mechanical means for feeding the closed packets along after the folding operations have been completed. In this the pivoted folding flap i^3 is operated by an arm i^{19} the pin i^{20} of which pivotally engages a block i^{21} adapted to slide in a slot i^{22} of a lever i^{23} pivoted on the cam stay i^{19} . The other end of the lever i^{23} is coupled to a bridle rod i^{24} by means of a connecting rod i^{25} having a roller i^{26} which co-acts with a cam i^{27} . On the side of the frame of the ma-

- outward so that when the plunger k^{21} re-tires they revert to the open position automatically so that the packets pass along without any friction or obstruction. In order to prevent the last packet fed into the dry chamber k^8 from falling backward on the retirement of the flap k^6 , a nose k^{26} having an inclined surface is disposed on the wall of the drying chamber behind which the packet springs when fed forward so as to be retained by the nose k^{26x} . The plunger k' carries the inclined surface b^{22} for working the stops b^{15} and grippers b^{16} as hereinbefore described.
- 15 The packets being fed along the chamber k^8 under considerable pressure from the flap k^6 they would unless restrained fall down at the delivery end when the side b^{17} is opened, in order to avoid this a regulatable flat spring k^{27} is fitted to the inside of the side b^{17} as shown in Fig. 10^e which will hold the series of packets in position until forced past the end thereof so as to be delivered from the chamber.
- 20 25 In an automatic machine of this description it is necessary to prevent contact of the gum pad g^9 with parts of the machine during the absence of paper therein and also to prevent the delivery of cigarettes on to the feeding platform e' in the absence of paper thereon. Should this occur the whole of the integrity of the operations is destroyed and in addition parts of the machine which should be perfectly free from gum would 30 35 become coated with gum and consequently the next packet dealt with by the machine would become stuck therein rendering the stoppage of the machine necessary to clear away all the obstructing material, the removal from the surface of the mechanism of all the gum which has been improperly applied thereto and all the loose cigarettes which had been improperly fed on to the feeding platform.
- 40 45 In order to avoid these serious inconveniences I provide in the slide d a recess l in conjunction with which is arranged a projecting nose l^1 carried at the end of a pivoted lever l^2 to which is connected an upwardly disposed lever l^3 the end of which is adapted to contact with a projection l^4 on the gumming frame g^7 so as to prevent the gumming frame g^7 from rocking into its operative position.
- 50 55 In order to insure the withdrawal of the projecting nose l^1 from the recess l before the movement of the slide d , I provide an angular surface l^5 on the gumming frame g^7 which contacts on its upward stroke with a 60 roller l^6 on the lever l^3 and positively withdraws the projecting nose l^1 from engagement with the slide d . To prevent the feeding of the cigarettes another arm l^7 is attached to the lever l^2 which under normal 65 conditions lies on a recess l^8 of the feeding finger f^7 but in the event of the nose l^1 entering the recess l the arm l^7 is raised so as to lie in the path of the slide f^7 and prevent the feeding movement taking place under the action of the spring f^{11} . When the paper is present on the surfaces of the slide d the nose l^1 cannot enter the recess l and consequently the normal operation of the machine can take place.
- 70 75 In order to remove any old dry gum from the gumming pad g^9 which may have accumulated during the stoppage of the machine and which it is necessary to get rid of before the operations are restarted I provide upon the gum throttle g^2 a scraper or knife g^{25} adapted to come into the path of the gumming pad g^9 during its reciprocating motion and to remove the dry gum therefrom and when this has been effected and the gum throttle g^2 is again adjusted for 80 working purposes, the scraper g^{25} is automatically removed from the path of the gumming pad g^9 . To avoid the dry gum from dropping into the machine and becoming an obstruction, I provide a receptacle g^{26} with catching lips g^{27} to receive the scrapings of partly dried gum, which receptacle can be emptied of its contents at any convenient time.
- 85 90 It is found to be desirable to provide simple means for finely adjusting the various parts of the mechanism so as to get the desired pressure and registration of position.
- 95 100 To adjust the cam rollers the journal c^{26} (Fig. 10^e) is made eccentric to the part c^{27} supported in its lever so that it can be moved about its axis and vary the position of the journal c^{26} relative to mechanism that it is operating. To take up the wear on the prominent part of the cams a method is shown in Fig. 6^d comprising an adjustable sliding block c^{28} arranged at the desired part and held by a screw c^{29} while an adjusting screw c^{30} is screwed into the body of the cam to force out and maintain the block c^{28} in 105 the proper position to produce the required motion. Wherever there is a reciprocating motion set up by cam in this machine an adjustable limit stop is provided against which the reciprocating part can abut to 110 give a positive terminal position or prevent over running of the parts due to momentum.
- 115 120 Motion is transmitted from any convenient source of power to a clutch pulley m by which the shaft m' forming the first motion shaft of the machine is driven. The second motion shaft m^2 is operated by means of spur gearing m^3 from the shaft m' . The cam b' , c^6 , d^{14} , e^5 , e^{13} , f^4 , f^{10} , g^{17} , h^8 , h^{12} , i^{13} , i^{27} , i^{34} , i^{38} , and k^6 are all rigidly mounted 125 upon the shaft m^2 . The clutch of the pulley m is operated by means of the foot treadle g^{22} through the mechanism m^4 .
- 130 So far as the description has gone the case referred to has been of a double char-

acter as illustrated in Fig. 10^b. I will now describe a single case as illustrated in Fig. 12^c and the modification in the mechanism that is necessary in order to carry out the 5 necessary operations.

The cut blank is illustrated in Fig. 12^a and is delivered on to the table e' in precisely a similar manner to the blank of the double packet already described. The 10 descent of the plunger e^0 folds the blank as illustrated in Fig. 12^b with the cigarettes therein. The gumming operation now takes place as previously described.

It will be noticed that in this single case, 15 corner pieces n are left on one side in order to stiffen the case. The next operation is the partially folding in of the corner pieces n and the complete folding down of the flap n' . This is effected by means of a reciprocating slide n^2 having angular projections n^3 which is moved in a direction transverse with the travel of the case along the channel i^0 by means of a lever n^4 , shaft n^5 , lever n^6 roller n^7 and cam n^8 . The flap n' is folded 20 down by means of an oscillating finger n^9 slidingly carried on an arm n^{10} and spring pressed by a spring n^{11} the arm n^{10} is oscillated by a forked lever n^{12} engaging with a pin n^{13} of a lever n^{14} mounted rigidly on the 25 shaft n^5 . The return motion of the slide n^2 and finger n^9 is effected by a spring n^{15} and lever n^{16} rigidly mounted on the shaft n^5 .

In order to complete the folding down of the rearmost flap n , a projecting finger o is 30 arranged on the forward end of one of the parts i^5 of the plunger i' which contacts with and folds in the side piece n before the case is moved along by the plunger i' . The forward corner piece n is folded down automatically as the case is pushed into the channel 35 i^0 . The flap p is folded down simultaneously with the final folding of the rearmost corner in a similar manner to that described for the double packet; and as the case is fed 40 along the channel i^6 , the top flap p' is similarly folded down as before described into the position shown in Fig. 12^a. The portions of the flap p' with the requisite gum are represented by p^2 in Figs. 12^b, 12^c, and 45 12^d; the squaring and consolidating of this single case being effected by the same mechanism as in the double packet.

In order to turn up the flap p^3 a helical surface o' is disposed at the side of the channel 50 i^6 so that as the case moves along the channel the flap p^3 is moved from a horizontal position into a vertical position as shown in Fig. 12^e. The only further step to be performed is the folding down of the flap p^4 which is 55 effected by means of a knife edge p^5 in conjunction with another helical surface p^6 which turns the flap p^4 from a horizontal position into an angular position until the case moves along a further distance opposite 60 65 a reciprocating slide p^7 operated by a lever

p^8 rigidly attached to the shaft n^5 . The edge of this slide p^7 squares the top corner edge of the case, after which the case is moved along a further step for the final closing operation. During the passage of the flap 70 p^4 along the helical surface, provision is made by means of grooves, ribs, or other convenient arrangements to prevent the gummed portions of the flap p^4 from coming into contact with parts of the machine 75 so that when the case arrives at its final stage the gummed parts are intact. The final closure is effected by means of a pivoted device q forming parts of the said walls of the channel i^6 , when in the closing position in 80 which it receives the case, the surface of the device q forms a continuation of the helical surface p^6 as shown in the drawing. The movement of the device q is effected simultaneously with and by being connected to 85 the slide p^7 through the connecting rod q' attached to the lower part of the device q the upper part of the device q being pivoted to an arm q^2 rigidly attached to the frame of the machine. The case when completed 90 can if necessary pass into a drying chamber in order to thoroughly dry the gum before final delivery from the machine.

In order that an audible indication can be given to the operator in the event of the 95 packets not coming out properly from the flap closing mechanism shown in Fig. 9, the falling roof i^9 is adapted to act as the agent for ringing an electric bell or other signal in the event of it not being able to drop 100 when the cam i^{13} leaves the roller i^{12} . To this end an electric contact i^{19} is mounted on the lever i^{11} (Fig. 9) in such a position to contact with another contact i^{20} on the connecting rod f^9 of the cigarette pushing finger 105 mechanism as shown in Fig. 5. An electric bell i^{21} and battery i^{22} are included in the electric circuit and when everything is running properly no contact is made and the bell is not rung, but immediately the lever 110 i^{11} fails to drop and to follow the surface of the cam i^{13} the contact i^{20} touches the contact i^{19} and the bell is rung indicating that the roof i^9 is not falling into its proper position.

As the momentum of the reciprocating parts of the machine is considerable when running at a high speed positive stops are provided to limit the motion at a definite terminal position for each motion.

What I claim is:

1. In a cigarette packet forming and filling machine the combination of a feeding mechanism by which the partially formed cases filled with cigarettes are pushed along a delivery channel and means by which the packet is supported on all four sides during the feeding operation together with a falling roof having a depending projection adapted to coact with the top flap and to square the 120 125 130

front end of the case on vertical pressure from said roof being applied to the packet case.

2. In a cigarette packet forming and filling machine the combination of a double-case formation and filling mechanism together with an aperture in the delivery channel means for pushing the double case downward into a V-form and reciprocating means by which each double case is completely folded and closed and is fed to a drying chamber for final consolidation.

3. In a cigarette packet forming and filling machine the combination of a double case formation and filling mechanism together with an aperture in the delivery channel means for pushing the double case downward into a V-form and reciprocating means by which each double case is completely folded and closed and is fed to a drying chamber for final consolidation also an inclined plane and retaining notch at the mouth of the drying chamber.

4. In a cigarette packet forming and filling machine the combination of a cigarette feeding device consisting of a hopper, a separating holder fitted with dividing means and located directly at the base of the hopper and adapted to hold two or more layers of cigarettes superposed on each other and to move transversely to the axes of the cigarettes, reciprocating feeding fingers working across said tray together with a constricting channel leading to the case folding mechanism for closing up the series of cigarettes fed at each operation and means by which the said holder and feeding fingers are operated co-actively, also the arrangement on the separating holder of means for catching the tobacco dust from the cigarettes and conveying it clear of the machine.

5. In a machine for manufacturing cases in paper, cardboard or similar material and for packing cigarettes and like goods therein, a stationary hopper for containing the goods to be packed, a sliding dividing tray adapted to hold one more layer than the required number of cigarette layers and disposed directly at the base of the hopper, mechanism for giving said sliding tray a motion relative to the hopper, and feeding fingers for pushing the bottom layer of cigarettes only out of the sliding tray.

55. 6. In a machine for manufacturing cases in paper, cardboard or similar material and for packing cigarettes and like goods therein, a stationary hopper for containing the goods to be packed a sliding tray disposed directly at the base of the hopper and having vertical partitions of such a height that the compartments formed accommodate one more layer than the required number of cigarette layers, mechanism for giving

said sliding tray a motion relative to the 65 hopper, and feeding fingers for pushing the bottom layer of cigarettes only out of the sliding tray.

7. In a cigarette packet forming and filling machine the combination of a cigarette hopper, a horizontally reciprocating tray constituting the base of said hopper and shorter 70 in length than the cigarettes so that both ends of the latter project over the chutes so as to remove all dust.

8. In a cigarette packet forming and filling machine the combination of a cigarette hopper, a horizontally reciprocating tray constituting the base of said hopper and shorter in length than the cigarettes so 80 that both ends of the latter project over the chutes so as to remove all the dust and limiting stops provided on the said tray to insure the latter stopping in a definite position each time so as to prevent the fingers 85 from colliding with the partitions and to permit the employment of very wide pusher fingers.

9. In a cigarette packet forming and filling machine the combination of folding fingers for turning over flaps formed on a cut and creased blank, projecting edges on said fingers for producing a square corner at the folded edges of said flaps, means for rotating said fingers to turn over said flaps and 95 independent means for retaining said fingers into the position to which they have been rotated.

10. In a cigarette packet forming and filling machine the combination of rotatable 100 fingers for folding over flaps on a cut and creased blank, means for rotating said fingers to fold over said flaps, means for subsequently drawing said fingers along said flaps and independent means for preventing 105 further rotation of said fingers during the movement of said fingers along said flaps.

11. In a cigarette packet forming and filling machine the combination of rotatable fingers for folding over flaps on a cut and 110 creased blank, means for rotating said fingers, means for imparting a linear motion along said flaps to said fingers, a projecting edge on each of said fingers for producing a square edged fold, and independent 115 means for guiding said fingers during their linear motion.

12. In a cigarette packet forming and filling machine the combination of a device for applying gum to a flap of a partly completed packet, a gum reservoir, a gumming roller for transferring gum from said reservoir to said device with which it is not in contact, but is separated therefrom by the thickness of the film of gum on said roller, 120 a screw passing through a lug fastened to the gumming frame, the said screw bearing against the gum reservoir, and a locking 125

screw passing through the latter and screwing into the center of the main screw to lock the same firmly against rotation and tightly against the gum reservoir, means for bringing said device into engagement with said flap and means comprising a recessed bridge for supporting said flap during such engagement.

13. In a cigarette packet forming and filling machine the combination of a multiple contact device for applying gum to a plurality of portions of a partly completed packet, a gum reservoir, a gumming roller for transferring gum from said reservoir to said device with which it is not in contact, but is separated therefrom by the thickness of the gum on said roller, a screw passing through a lug fastened to the gumming frame, the said screw bearing against the gum reservoir, and a locking screw passing through the latter and screwing into the center of the main screw to lock the same firmly against rotation and tightly against the gum reservoir, means for bringing said device into engagement with said flap and means for supporting said flap during such engagement, comprising a bridge member having recesses therein opposite each portion of the flap to be gummed.

14. In a cigarette packet forming and filling machine the combination of means for producing a filled packet consisting of two similar sections in the same plane, means for positively bending said packet between said sections and independent means for completing said bend to bring said sections in contact with one another in parallel planes.

15. In a cigarette packet forming and filling machine the combination of means for producing a filled packet consisting of two similar sections in the same plane, a rocking flap member for bending said packet between said sections and a reciprocating flap member for completely closing said sections one upon the other.

16. In a cigarette packet forming and filling machine the combination of means of two similar sections in the same plane, and means for positively closing said sections one upon the other in two successive and distinct stages.

17. In a cigarette packet forming and filling machine the combination of means for producing a filled packet, consisting of two similar sections in the same plane, means for positively causing one of said sections partly to close on the other section and means for positively completing the closing movement and for subsequently moving said closed packet forward.

18. In a cigarette packet forming and filling machine the combination of means for producing a series of folded and gummed

packets, a tubular drying chamber for said packets, means for causing an intermittent progressive movement of said packets through said chamber, alternately expanding and contracting walls for said chamber and means for positively collapsing the packets into V-form.

19. In a cigarette packet forming and filling machine the combination of means for producing a series of folded and gummed packets, a tubular drying chamber for said packets, means for causing an intermittent progressive movement of said packets through said chamber, alternately expanding and contracting walls for said chamber and means for positively collapsing the packets into V-form and means for positively preventing the falling backward of the packets on the return of the pusher.

20. In a cigarette packet forming and filling machine the combination of means for producing a series of folded and gummed packets, an extended drying chamber of rectangular cross section through which said packets pass in succession and means for causing more than one of the walls of said chamber to move alternately outward and inward.

21. In a cigarette packet forming and filling machine the combination of means for producing a series of folded and gummed packets, an extended drying chamber of rectangular cross-section, means for causing one of the walls of said chamber to move alternately outward and inward and means operated by said wall for causing another wall to perform a similar movement.

22. In a cigarette packet forming and filling machine the combination of means for producing a series of folded and gummed packets, a drying chamber for said packets, means for positively introducing each packet in succession into said chamber, a pair of pivoted members constituting two of the walls of said chamber, means for causing one of said members to move about its pivot to release the packets in said chamber and means operated by said member to cause a similar movement of the other member.

23. In a cigarette packet forming and filling machine, the combination of means for producing a series of folded and gummed packets, an extended drying chamber of rectangular cross-section through which each of said packets passes in succession expanding and contracting walls for said chamber and an inwardly extending projection on one of said walls to prevent the packet rolling backward.

24. In a cigarette packet forming and filling machine, the combination of means for producing a series of folded and gummed packets, a chamber for said packets wherein the folding operation is completed and one

side of which is movable relatively to the other sides, means for effecting the movement of the said side of the chamber and means for indicating the presence of an imperfect packet within this chamber, and a drying chamber to which the packets are subsequently delivered having alternately

expanding and contracting walls for maintaining the packets in their fully formed condition for a predetermined time.

ALFRED GODFREY.
